TOBACCO FEEDING DEVICE

George Zint, Wapakoneta, Ohio

Application August 3, 1944, Serial No. 547,859

7 Claims. (Cl. 131—44)

The invention aims to provide a novel and advantageous device for feeding measured quantities of cigarette tobacco into the tobacco-receiving channel of a hand-actuated cigarette rolling machine, to insure that the cigarettes rolled by said machine shall be uniform instead of having the tobacco too loose in some and too tight in others, as now frequently happens.

In carrying out the above end, further objects are to provide a simple and inexpensive, yet an efficient and easily operable device; to provide for the effective feeding of shredded tobacco, the various strands or shreds of which are intermingled and tend to catch on each other; and to provide for varying the amount of tobacco fed to the rolling machine, according to the wishes of the user.

With the foregoing in view, the invention resides in the novel subject matter hereinafter described and claimed, description being accomplished by reference to the accompanying drawings.

Fig. 1 is a top plan view of the feeding device.

Fig. 2 is a side elevation.

Fig. 3 is a front elevation.

Fig. 4 is a vertical longitudinal sectional view substantially on line 4—4 of Fig. 1, showing the feeding device operatively positioned with respect to a known type of cigarette rolling machine.

A preferred construction has been shown in the drawings and will be specifically described, with the understanding, however, that within the scope of the invention as claimed, variations may be made.

The device includes a substantially flat casing 5, both ends of which are open, the front end being adapted for insertion into the tobacco-receiving channel 6 formed by a loop of the usual belt 7 of a conventional cigarette rolling machine 8. The top of the casing 5 is formed throughout its width with a slot 9, and said top is provided with a tobacco measuring hopper 10 surrounding said slot.

A plunger 11 is slidable within the casing 5 and has an appropriate rearwardly projecting operating handle 12. When filling the tobacco measuring hopper 10, the plunger 11 occupies a position sufficiently forward to close the slot 9 and form a bottom for said hopper. Then, when the plunger 11 is pulled rearwardly to open the slot 9, the tobacco may enter the casing from the hopper 10. Then, by forwardly sliding the plunger, the tobacco may be forced into the channel 6 as shown in Fig. 4. When this has been accomplished, the plunger is held and the casing is

slid rearwardly, leaving the tobacco held in the channel by the plunger. The entire device is then moved aside from the rolling machine 8 and the latter is operated after properly placing the usual gummed cigarette paper.

More or less granulated tobacco will readily fall through the slot 9 into the casing 5 when the plunger 11 is pulled rearwardly, but shredded tobacco will not descend so readily. I have found, however, that if the slot 9 and the hopper 10 are oblique to the length of the casing 5, reciprocation of the plunger 11 will feed all of the measured tobacco down into the casing to be forced into the machine. It is, therefore, preferable that this oblique characteristic be embodied in the machine, as shown, and this accounts for the similar position of the tobacco supply hopper 13 which is mounted upon the rear portion of the casing 5. This hopper includes a bottom 14 which extends forwardly to the measuring hopper 10, and a front wall 15 which is spaced rearwardly from the front end of the bottom 14 and is also spaced upwardly from said bottom, permitting the tobacco to be readily pulled forwardly with the fingers from the hopper 13 into the measuring hopper 10. It is preferable to provide the hopper 13 with side wall extensions 16 which project forwardly beyond the wall 15 and prevent the tobacco from spilling laterally from the bottom 14 while said tobacco is being pulled into the measuring hopper 10.

Provision has been made for varying the capacity of the measuring hopper 10. In the present disclosure, a plate 17 rests slidably upon the front portion of the bottom 14, the front end of said plate being provided with a downwardly projecting flange 18 which constitutes a rear wall for the measuring hopper 10. The plate 17 has upwardly extending side walls 19 lying slidably against the inner sides of the side wall extensions 16 of the hopper 13, and bolt-and-slot adjusting means 20 suitably connect said walls 19 and extensions 16 to permit forward or rearward adjustment of the plate 17 and its flange 18, and to clamp said plate in any selected position. It is preferable that a scale 21 (Fig. 2) be provided on one end of the measuring hopper 10 to aid in setting the plate 17 and its flange 18 according to the quantity of tobacco to be measured at each operation of the device.

In operation, the front end of the casing 5 is inserted into the tobacco receiving channel 6 of the cigarette rolling machine 8. The plunger 11 is then slid forwardly sufficiently to close the slot 9. Tobacco may now be pulled from the hopper

13 into the measuring hopper 10 until the latter is properly filled, whereupon the plunger 11 is pulled rearwardly to open the slot 9. When this occurs, if the tobacco be granulated, it will all gravitate promptly into the casing 5 ahead of the plunger 11. If shredded tobacco is being used, however, it will be necessary to reciprocate the plunger 11 a number of times before all of the tobacco will feed down into the casing in front of said plunger. When this plunger is now pushed forwardly, the measured quantity of tobacco will be supplied to the channel 6. Then, while holding the plunger 11 against rearward sliding, the rest of the device is slid rearwardly, leaving the tobacco in the channel 6. Then, when the plunger is disengaged from the tobacco, the machine 8 may be operated in the usual manner after properly placing the usual gummed cigarette paper.

Excellent results have been obtained from the construction shown and described and it is, therefore, preferably followed. However, attention is again invited to the possibility of making variations within the scope of the invention as claimed.

I claim:

1. A filling device for a cigarette rolling machine, comprising a substantially flat casing having an open front end for insertion into a tobacco receiving channel of the rolling machine, the top of said casing having a tobacco entrance slot and a tobacco measuring hopper surrounding said slot, and a forwardly and rearwardly slideable plunger in said casing, said plunger being movable to one position in which it closes said slot and forms a bottom for said tobacco measuring hopper, being movable rearwardly from said one position to open said slot and permit the measured tobacco to enter said casing, and being then movable forwardly to force the measured tobacco into the machine.

2. A filling device for a cigarette rolling machine, comprising a substantially flat casing having an open front end for insertion into a tobacco receiving channel of the rolling machine, the top of said casing having a tobacco entrance slot and a tobacco measuring hopper surrounding said slot, a forwardly and rearwardly slideable plunger in said casing, said plunger being movable to one position in which it closes said slot and forms a bottom for said tobacco measuring

hopper, being movable rearwardly from said one position to open said slot and permit the measured tobacco to enter said casing, and being then movable forwardly to force the measured tobacco into the machine, and a tobacco supply hopper mounted on the rear portion of said casing and having a bottom which extends forwardly to said measuring hopper, said supply hopper having a front wall spaced rearwardly from the front end of said bottom and spaced above said bottom, whereby tobacco may be pulled forwardly with the fingers from said supply hopper to said measuring hopper.

3. A structure as specified in claim 2; said supply hopper having forwardly projecting side wall extensions to prevent the tobacco from spilling laterally while it is being pulled forwardly to said measuring hopper.

4. A structure as specified in claim 1; said measuring hopper having an inwardly and outwardly movable wall for changing its capacity, and means for holding said wall in any selected position.

5. A structure as specified in claim 2; together with a plate lying slidably upon the front portion of said supply hopper bottom, said plate having a downwardly projecting flange at its front end constituting a rear wall for said measuring hopper, said plate and its flange being forwardly and rearwardly adjustable to vary the capacity of said measuring hopper, and means for securing said plate in any selected position.

6. A structure as specified in claim 2; together with a plate lying slidably upon the front portion of said supply hopper bottom, said plate having a downwardly projecting flange at its front end constituting a rear wall for said measuring hopper, said plate and its flange being forwardly and rearwardly adjustable to vary the capacity of said measuring hopper, said supply hopper having forwardly projecting side wall extensions rising from the forwardly projecting portion of its bottom, said plate having upstanding side walls contacting slidably with the inner sides of said side wall extensions, and means for securing said side walls of said plate to said side wall extensions after adjustment of said plate.

7. A structure as specified in claim 1; said slot and measuring hopper being oblique to the length of said casing, for the purpose set forth.

GEORGE ZINT.
